UNITED STATES PATENT OFFICE.

JOHN MURRAY, OF TACOMA, WASHINGTON.

SAW-GUARD.

No. 893,087.

Specification of Letters Patent.

Patented July 14, 1908.

Application filed November 9, 1905. Serial No. 286,584.

To all whom it may concern:

Be it known that I, JOHN MURRAY, a citizen of the United States, residing at Tacoma, in the county of Pierce and State of Washington, have invented a certain new and useful Improvement in Saw-Guards with Dimension Gage Attachments for Shingle-Clippers; and I do hereby declare that the following is a true and full, clear, and exact account or description of the invention, such as will enable other persons skilled in the business to which it appertains to successfully make and use the same.

My invention relates to improvements in saw guards with dimension attachments, and has for its object a guard so constructed and related to the machine that it will greatly lessen, if not entirely prevent the danger of persons becoming injured by contact with the movable parts of the machine.

With the above and other objects in view, my invention further consists in the novel details of construction and combination of parts to be fully hereinafter described and later pointed out in the claims.

In the drawings:—Figure 1 is a view in perspective of a shingle trimming machine equipped with my improved guard. Fig. 2 is a perspective view of a guard and dimension attachment in detached relation to the machine. Fig. 3 is a like fragmentary view of a portion of one end of the guard. Fig. 4 is a similar view of the portion of the opposite end of the guard; and Fig. 5 is a perspective view of the parts of the dimension attachments.

1 designates the floor on which the shingle trimming machine 2, rests; 3, the wall; 4, a ledge; and 5, a raised portion of the floor.

40 The guard consists of a member 6, formed of a strip of material having an intermediate portion inclined upwardly as at 7, from which inclined part the member continues in a major straight portion as at 8, the end of the latter being inclined downward as at 9. 10 denotes a second member of which the guard is composed consisting of a straight major portion and an upwardly inclined inner end 11, slotted at 12, and adjustably secured to end 9, of member 6, by means of the set screws 13.

As shown in Fig. 1, members 6 and 10 at their outer ends are secured to the bed of the machine as at 14 and 15, in such position, 55 that the several members in their assembled position will overlie the saw 16. 17, design-

nates a guard member formed of a section of flat metal which is formed with a right angular lip 18, having threaded perforations to receive screws 19 which extend through inclined portions 7 and by means of which member 17, is removably held to portion 7. The member 17 performs the function of preventing contact of the operators hand with the moving saw when grasping the shingles 65 after the sawing operation.

In conjunction with my guard I employ a dimension attachment which comprises two members, each consisting of a flat bar 20, attached at 21, to straight portion 8, so as to 70 project at right angles therefrom as shown. The outer ends of bars 20, are longitudinally slotted as at 22 and adjustably carry members 23 consisting of a right angular element which is engaged by a set screw 24, which 75 normally passes through slot 22. It will thus be seen that members 23 may be adjusted towards or away from the saw to vary the width of the shingles since the latter is determined by the distance existing between the saw 16 and the depending part of member 23. It will be further noted that by adjustment of screws 13, the distance between portion 8 of the guard and the uppermost part of the saw 16, may be regulated as 80 desired. As each side of the machine is equipped with a guard, I preferably brace the two by the employment of the bar 25, which extends transverse of the machine and is secured at its ends by screws 26, to the 90 portion 8, thereby providing mutual support and adding rigidity to the several guards.

Having thus fully described my invention, what I claim as new and desire to secure by Letters Patent, is:—

1. A guard for shingle machines comprising in combination with a shingle machine, a member having two straight portions, a connecting inclined portion between said straight portions, and a downwardly extending end, one end of said member being secured to the machine bed, a second member having one end secured to the machine bed and having its opposite end extending upwardly and adjustably secured to said downwardly extending end of the first member, and a third member having a right angular lip secured to said inclined portion of the first member to extend downwardly on one side of the saw.

2. A guard and dimension attachment for shingle trimming machines comprising in

combination with a shingle trimming machine, a pair of members each connected adjacent one of its ends to the machine bed, an adjustable connection between said members and gage members secured to said guard and composed of projecting bars and right angular members adjustably connected to said bars.

3. A guard for rotary saws consisting of a member having a horizontal end and an inclined end, a second member having a horizontal end, an inclined intermediate portion, and a downwardly extending end adjustably secured to said inclined end of the first member.

4. A guard for rotary saws consisting of a

member having two straight portions, a connecting inclined portion between said straight portions and a downwardly extending end, a second member having an upwardly extending end adjustably secured to said downwardly extending end of the first member, and gage members carried by one of said straight portions of the first member.

In testimony whereof I have signed my name to this specification in the presence of two subscribing witnesses.

JOHN MURRAY.
